UNITED STATES PATENT OFFICE.

WILLIAM H. ROSE, OF BALTIMORE, MARYLAND.

DISINFECTING APPARATUS.

No. 822,019.

Specification of Letters Patent.

Patented May 29, 1906.

Application filed May 4, 1905. Serial No. 258,852.

To all whom it may concern:

Be it known that I, WILLIAM H. ROSE, a citizen of the United States, and a resident of Baltimore, Maryland, have invented certain new and useful Improvements in Disinfecting Apparatus, of which the following is a specification.

This invention relates to improvements in that class of disinfecting apparatus in which 10 the liquid contained in a suitable reservoir is slowly discharged therefrom, preferably by capillary attraction.

The objects of the invention are to provide a disinfecting apparatus which is capable of 15 being filled nearly to its full capacity and which shall have a uniform discharge.

A further object of the invention is to provide a disinfecting apparatus which is peculiarly adapted for use in railway-cars, 20 steamships, and other vehicles.

The invention will be described in connection with the accompanying drawings, in which—

Figure 1 is a sectional view of an apparatus 25 embodying my invention, showing the tank full. Fig. 2 is a similar view showing the tank nearly empty; and Fig. 3 is a plan view looking down from the line 3 3, Fig. 1. Fig. 4 is a section through the filling-opening.

The present invention is in the nature of an 30 improvement upon the disinfecting device disclosed in my Patent No. 641,548, dated January 16, 1900.

Referring to the drawings, 10 indicates the 35 tank or receptacle for the disinfecting fluid, which may be of any suitable size, shape, and material. Within the receptacle is a float 11, which may also be of any suitable shape or material. As shown, the float is constructed 40 of wood. It is provided with a transverse bar or support 12 for a wick-tube 13, said tube being of sufficient length to project above the level of the fluid in the receptacle, and its lower end being adapted for connection 45 to a flexible tube 14, which connects the tube 13 to a discharge-tube 15, fixed in the bottom 16 of the receptacle 10. In the wick-tube 13 is a short wick 17, which hangs over the side of the tube with its end in the fluid.

The branch of the wick within the tube should 50 be longer than the branch which dips in the fluid, so that a siphoning action will take place. In operation the wick absorbs the fluid by capillary attraction and discharges it 55 very slowly into the tube by reason of the

siphoning action, due to the difference in length of the branches or "legs" of the wick.

To prevent the flexible tube 14 from kinking or collapsing, I preferably place within it a flexible support for the walls of the tube, 60 such as the chain 18.

The cover 19 of the tank is provided with a filling-opening 20, which is preferably kept normally closed by a pad or stopper 21, supported on a spring-plate 22. A keeper 23 65 may be arranged to prevent the spring 22 from being injured or detached while the receptacle is being filled.

The base 24 of the apparatus may be of any desired form, that shown being the same 70 as illustrated in my previous patent. The fluid from the pipe 15 drops upon a pad of absorbent material 25 in the bottom of the base 24. A part of the fluid evaporates through openings 26, and the remainder drops 75 from the discharge-pipe 27. Any suitable means may be used for connecting the apparatus to a wall or other support. As shown in Fig. 3, the back of the receptacle has extensions 28, through which the nails or 80 screws may be driven into the wall to support the apparatus.

The apparatus may be refilled at any time by depressing the spring 22 and pouring the fluid in through the opening 20. The opening is arranged directly over the wick 17, so that the inflowing fluid will drench the wick and prepare it for immediate action. It will be seen that the fluid cannot splash out of the receptacle, and the apparatus is therefore 85 especially useful for railway-cars, steamboats, and other vehicles. The float preferably has a central opening 29, and the wick is preferably arranged near the center of the opening. This insures the wick being immersed in the 90 fluid uniformly, regardless of the splashing of the fluid on the sides of the vessel and regardless of the angle at which the apparatus may be held. As the fluid becomes exhausted 95 the float sinks and the discharge-tube 14, which should be of soft rubber or similar material, coils on the bottom of the receptacle, as shown in Fig. 2.

The apparatus described permits the vessel to be filled nearly to the top and provides 100 for a very slow and uniform discharge, and hence a single filling will last for a considerable period. The receptacle may be refilled quickly without removing or deranging any part of the apparatus.

Having described my invention, what I claim, and desire to secure by Letters Patent, is—

1. In a disinfecting apparatus, the combination with a receptacle for disinfecting fluid and a float therein, of a flexible tube depending from the float and connecting the float with a discharge-opening, and a wick carried by the float and arranged to discharge into said tube.
2. In a disinfecting apparatus, the combination with a receptacle for disinfecting fluid, of a float therein, a depending flexible tube having one end connected centrally with the float and having its other end connected with a discharge-opening, and a wick carried by said tube and depending in the fluid, said wick being arranged to discharge said fluid into said tube.
3. In a disinfecting apparatus, the combination with a receptacle for disinfecting fluid having a discharge-opening in its lower end, of a float within the receptacle, a flexible tube connected with the float and with the discharge-opening, and capillary means carried by the float for admitting a restricted flow of fluid to said flexible tube.
4. In a disinfecting apparatus, the combination with a receptacle for disinfecting fluid having a discharge-opening in its lower end, of a float within the receptacle, a flexible tube connected with the float and with the discharge-opening, and a wick having one end communicating with said flexible tube and its other end depending in said fluid.
5. In a disinfecting apparatus, the combination with a receptacle having a discharge-opening in its lower portion, of a float, a flexible tube connecting the float with said discharge-opening, means in said tube to prevent it from collapsing, and means carried by the

float for admitting fluid to the upper end of the tube.

6. In a disinfecting apparatus, the combination with a receptacle having a discharge-opening in its lower portion, of a float, a flexible tube connecting the float with said discharge-opening, a chain in said tube to prevent it from collapsing, and means carried by the float for admitting fluid to the upper end of the tube.

7. In a disinfecting apparatus, the combination with a receptacle for disinfecting fluid having a discharge-opening in its lower portion, of a float carrying a wick-tube arranged to extend above the fluid, a flexible tube connecting said wick-tube with said opening, and a wick arranged in said wick-tube and having its outer end depending in the fluid.

8. In a disinfecting apparatus, the combination with a receptacle for disinfecting fluid, a float within the receptacle and a wick carried by the float, of means for conveying fluid from the wick to a discharge-opening in the receptacle, a filling-opening arranged above said wick, and means for normally closing said opening.

9. In a disinfecting apparatus, the combination with a receptacle for disinfecting fluid having a discharge-opening, of a float therein having a central opening, a wick-tube supported centrally in said opening, a wick in said tube, and a flexible tube connecting said wick-tube with the discharge-opening.

In testimony whereof I have signed my name to this specification in the presence of two subscribing witnesses.

WILLIAM H. ROSE.
